FLUORESCENT LIGHTING FIXTURE

Peter J. Parlato, Harrington Park, N. J., assignor
to Parco Lighting Equipment Co., Inc., New
York, N. Y., a corporation of New York

Application April 10, 1945, Serial No. 587,594

3 Claims. (CL. 201—64)

1

My present invention relates to fixtures for fluorescent lights and more particularly to a novel base or channel support for a fluorescent light wherein a housing is provided integral with the base or support for the ballast or resistance wire commonly necessary in fluorescent lighting circuits.

Heretofore in the construction and operation of fluorescent lighting fixtures, it has been common to provide a resistance or other form of ballast for the fixture in a separate housing or container which was separately wired and independently secured to the principal housing of the fixture.

My novel device contemplates a stand, base or support for a fluorescent light fixture wherein the said stand, base or support will be made entirely or substantially of insulating material, preferably of a porcelain or other ceramic material and will be integrally molded in a support and housing for the resistance wire or other form of ballast.

My invention further contemplates novel special housings and supports for a resistance wire or other form of ballast for a fluorescent lighting fixture.

The foregoing and many other objects of my invention will become apparent in the following description and drawings in which

Figure 1 is a view in perspective partially broken away of my novel fluorescent lighting fixture stand, base or support.

Figure 2 is a bottom view of the member of Figure 1.

Figure 3 is an end view of a modified form of insulating resistance wire support.

Figure 4 is a cross-sectional view taken on line 4—4 of Figure 3 looking in the direction of the arrows.

Figure 5 is a view in elevation of the cap member of Figure 4 taken from line 5—5 of Figure 4 looking in the direction of the arrows.

Figure 6 is an end view of the cap member of Figure 5 taken from line 6—6 of Figure 4.

Figure 7 is a bottom view of the cap member of Figures 4, 5 and 6 taken from line 7—7 of Figure 5 looking in the direction of the arrows.

Figure 8 is a view in perspective of a portion of the cap member of Figures 4, 5, 6 and 7.

Referring now to Figures 1 and 2, I have here shown a fluorescent light fixture lamp stand, base or support 10 formed of insulating material, preferably porcelain or other ceramic material, molded into shape. The member 10 comprises a top wall 11, front and back walls 12 and 13 respectively and side walls 14, 14.

The lower edge of each of the walls 12, 13 and

2

14 is recessed at 15, 15 to provide for ventilation beneath the bottom of the base 10. The walls 12, 13 and 14 serve to space the undersurface of the top wall 11 from the surface on which the stand rests.

The top wall 11 may have formed therein a recess 17 to accommodate pencils, pens and the like, although obviously this is not essential but adds to the appearance of the device.

The undersurface of the top wall 11 has a substantially rectangular bulge 20 therein which is provided with a recess 21 for a resistance wire. As seen in Figure 2, this recess may be a continuous recess contained entirely within the bulge 20 and extending from the larger recess 22 in a sinusoidal member around to the other larger recess 23. The bulge 20 may be formed in various different ways in order to provide a continuous path for the resistance wire. Where the top wall 11 is sufficiently thick, then the bulge 20 is not necessary, and the recess 21 may be formed pressed or molded right into the undersurface of the top wall 11.

The resistance wire mounted in the recess 21 may be connected to suitable connecting elements indicated at 25, 26 in the larger recesses 22, 23. After the resistance wire is mounted in the recess 21 and connected to the connecting elements 25, 26, a covering member 30 of ceramic material may be mounted over the recess 21, the said covering member 30 having a recess exactly matching the recess 21 and thus confining the resistance wire within the recess 21.

The covering member 30 may be secured in any suitable manner as, for instance, by screws or bolts entering the threaded openings 32, 32 in the bulge 20. It will be obvious, of course, that where the recess 21 is sufficiently deep, then the covering member 30 need have no special formation on the interior surface thereof but need only be a flat plane structure, smooth on both sides.

A suitable opening 35 in the back wall 13 may be provided for the connecting cord 36 which will connect the fixture to a suitable source; the wires 45 from cord 36 are connected through the ballast supported in recess 21, and the on-off switch 40 to the fluorescent light tube and its starter member, supported on post 38 in a manner well known in the art.

50 The top wall 11 is provided with an opening 37 suitably formed to receive and support a hollow lamp standard 38 through which the wiring may be led up to the fluorescent light bulb.

Where desired, the back wall 13 of the base member may be provided with an opening 50 to

receive a suitable receptacle for the starter member, commonly used with fluorescent fixtures. It is obvious of course, that any other wall of the base member 10 may be provided with the opening 50 for the support of the starter receptacle.

By this means, a base standard or support is provided for a fluorescent lighting fixture wherein the resistance or other ballast member is spaced and supported in a portion of the base which is integral with the base.

Obviously, the entire base 10 with all of the formations required for support of the resistance or other form of ballast and the other elements described may be molded at one time.

In Figures 3 through 8, I have shown a modified form of ballast supporting unit which may be made individually for incorporation in a lighting fixture or which may be extended to form the principal support for the fluorescent light tube.

Essentially, the resistance wire support comprises a rod 60 of insulating material, preferably molded or extruded ceramic material, having a plurality of longitudinal openings 61, 61 therethrough. The resistance wire may be passed entirely through one of the openings 61, then around the end of the rod as indicated at 62, and into an adjacent opening 61, and then around the opposite end of the rod and through the next opening 61. The number of longitudinal openings 61 required is determined by the length of the unit 60 and the length of the resistance wire which must be used.

An insulating spacer or cover member 65 is provided concentrically with the rod 60 and is secured to the rod 60 and spaced therefrom by the flange members 67.

In the preferred form, the entire unit consisting of rod 60, the flange member 67 and the outer insulating tubular member 65 is extruded through a single die to form an integral structure.

The tubular member 65 serves as a ceramic housing for the entire unit further insulating the unit; and the air spaces formed by the flanges 67 and the tubing 65 provide an effective heat insulation in combination with the insulating material of the tubing 65.

Each end of the rod 60 is provided with a tapped opening 70, 70 to receive the screw 71 which supports the cap 72 in position. The cap 72, it will be noted, is so arranged that it covers the exposed ends of the rod 60 on each side while the cap itself is hollowed out, so that no pressure is exerted on the connecting portions 62 of the resistance wire across the end faces of the rod 60.

As seen in Figures 4 through 8, the cap 72 comprises a substantially circular member having an annular flange 73 projecting from a circular base 74. The inner diameter of the annular flange 73 is slightly greater than the outer diameter of the rod 60 so that the flange 73 may encase the end of the rod 60. The outer tubular member 65 is cut back slightly at 77 to permit the annular flange 73 to encase the end of the rod.

In an alternate and obvious modification, only the flange members 65 need be cut back for this purpose.

The center of the circular portion 74 of the cover member is provided with a circular boss 80 having an opening 81 which, when the cap is in position, registers with the tapped opening 70 in the end of the rod 60. The screw 71, passing through the opening 81 of the boss 80 and into the tapped opening 70 of the rod, secures the cap in position.

Each of the ends of the rod 60 may be provided

with one or more slots 83 to receive small inward radial extensions 82 of the annular flange 73 as the cap is moved into position on the end of the rod 60. In this way, the cap 72 is locked against any rotation which would tend to loosen the screw 71, and the angular position of the cap with respect to the rod is predetermined.

The cap is, of course, preferably made of ceramic material similar to that of which the rod 60 and its tubular housing member 65 is made. The cap 72 is secured in any suitable manner to a base member 85 (shown in perspective in Figure 8 and in the bottom view of Figure 7).

As shown in Figures 4 and 5, the annular flange 73 is recessed at 86 so that the inner surface 87 of the foot member 85 may be substantially flush with the surface of the annular flange 73. The said inner surface 87 is slightly recessed, however, so that it may engage the lower portion of the end surface of rod 60. Surface 87 of the base member 85 is provided with a half tubular slot 89 to provide a wire-way to lead out the end of the resistance wire mounted in the rod 60. The lower supporting portion 90 of the member 85 is provided with a half tubular slot 91 communicating with the slot 89. Slots 89 and 91 thus provide a wire-way for the wire which may be led out between the supporting extensions 93 of the base member 85.

Extensions 93 of the base member 85 are sufficiently long to provide an efficient support for the entire unit and efficient means for securing the unit where desired. Obviously, a similar cap member 72 with its associated support or foot 85 is mounted at either end of the unit 60-65.

In preparing the unit, the wire is threaded through the openings 61, as previously pointed out, and the wire end on each side is pulled down into position where it will register with the slot 89 in the surface 87 of the foot member carried by the cap 72. The cap is mounted in position with the wire end extending through the slot 89 and then the wire end is bent at right angles up into the slot 91 and out between the extensions 93.

The unit, as above set forth, may be provided as a simple resistor unit for incorporation in a lighting fixture. Thus, the unit 60-65 with its caps may be utilized in place of the bulge 20 and wire-way 21 of the base member of Figures 1 and 2. Unit 60-65 may, however, be extended to have a sufficient length to form a supporting structure for the fluorescent light bulb itself. Thus, for instance, unit 60-65 may be utilized in place of the standard 38 of Figures 1 and 2; or the unit 60-65 may be made sufficiently long to act in place of the housing which supports the fluorescent light tube. In this latter case, the cap member may be modified to carry appropriate socket members and the starter unit may be mounted in any suitable position either in a receptacle carried by the outer tube 65 or in the cap member.

While the unit 60-65 is shown as of circular cross section, it may obviously be made of square cross section with the rod 60 square and the tube 65 square, or of hexagonal cross section, or of any other appropriate cross section; and it will be obvious of course that the tube 65 may have a cross section which need not necessarily correspond to the cross section of the rod 60. That is, the tube 65 may have a hexagonal square or other cross section of pleasing or decorative appearance, while the rod 60 may be circular or of different cross section.

In the foregoing, I have described my invention only in connection with preferred specific embodiments thereof. Since many variations and modifications of my invention should now be obvious to those skilled in the art, I prefer to be bound not by the specific disclosures herein set forth but only by the appended claims.

I claim:

1. A base for a fluorescent lighting fixture, said base being formed of insulating material, said base having a substantially plane supporting surface and means for spacing the undersurface of said supporting surface above any support on which said base may rest; means on the undersurface of said supporting surface for supporting a resistance wire; said last mentioned resistance wire supporting means being integral with the undersurface of said supporting surface; and comprising an extension from said undersurface of said supporting surface; said extension having a recess therein for confining the resistance wire.

2. A base for a fluorescent lighting fixture, said base being formed of insulating material, said base having a substantially plane supporting surface and means for spacing the undersurface of said supporting surface above any support on which said base may rest; means on the undersurface of said supporting surface for supporting a resistance wire; said last mentioned resistance wire supporting means being integral with the undersurface of said supporting surface and comprising an extension from said undersurface of said supporting surface; said extension having a recess therein for confining the resistance wire;

10

35

and a cover plate of insulating material secured to said extension over said recess and enclosing said resistance wire.

3. A base for a fluorescent lighting fixture, said base being formed of insulating material, said base having a substantially plane supporting surface and means for spacing the undersurface of said supporting surface above any support on which said base may rest; means on the undersurface of said supporting surface for supporting a resistance wire; said supporting means for said resistance wire comprising a recess in the undersurface of said supporting surface, and a cover plate of insulating material secured to said undersurface of said supporting surface over said recess and confining the resistance wire within said recess; said cover plate having a recess in its upper surface register with the recess in the undersurface of said supporting surface.

PETER J. PARLATO.
